UNITED STATES PATENT OFFICE

JAMES A. REARDON, OF SEATTLE, WASHINGTON.

ELECTRIC HEATER.

No. 857,485.

Specification of Letters Patent.

Patented June 18, 1907.

Application filed February 28, 1906. Serial No. 303,492.

To all whom it may concern:

Be it known that I, JAMES A. REARDON, a citizen of the United States, residing at Seattle, in the county of King and State of Washington, have invented a new and useful Electric Heater, of which the following is a specification.

This invention relates to electric heaters, and has for its principal object to provide a device of simple construction which may be conveniently used for the heating of small quantities of water in basins or the like, or for other purposes where an electric current may be conveniently employed for heating purposes.

A further object of the invention is to provide a resistance element carrier in the form of a helically grooved cylinder of porcelain or other non-conducting material, in which provision is made for the convenient placing of a double winding of wire of high resistance, a further object in this connection being to so construct a grooved cylinder that while acting to prevent short circuiting of the coil, it will, also, shield the wire and prevent contact between the latter and the casing of the heater.

A still further object of the invention is to provide an electric heater which may be placed in any liquid containing vessel without interfering with the free circulation of water through the heater, no matter what the position of the latter may be.

A still further object of the invention is to provide an electric heater in which all of the current conducting elements are held from contact with any portion of the exterior of the casing, so that there will be no danger of shock in case a portion of the body is immersed in the water while the heater is in operation, and any portion of the handle or casing of the heater may be grasped without the slightest danger of grounding any portion of the current through the body.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a sectional elevation of an electric heater constructed in accordance with the invention. Fig. 2 is a detail elevation, on an enlarged scale, of the cylinder for carrying the resistance element. Fig. 3 is a sectional plan view of the cylinder. Fig. 4 is a detail view of a portion of the cylinder showing the manner in which the bight of the resistance wire is held. Fig. 5 is a sectional view of the handle on an enlarged scale. Fig. 6 is a detail view of a portion of the switch.

Similar numerals of reference are employed to indicate corresponding parts throughout the several figures of the drawings.

In carrying out the invention, a cylinder 10 is formed of porcelain or similar material, and the periphery of this cylinder is provided with a pair of helical ribs 11 that extend from end to end of the cylinder and define grooves in which the wire 12 is wound. At a point near one end of the cylinder one of the ribs is cut away and provided with a notch 15 which receives the bent portion of the wire, and the latter is thence wound double through the grooves, each single turn being separated from the others by the ribs until, at the opposite end of the cylinder, the ribs are provided with openings 16 for the passage of the ends of the wire. The ribs are preferably so spaced as to permit the ready winding of the wires within the grooves, and are of such height that no portion of the wire will be exposed, the wires being thus kept from either mechanical or electrical contact with the casing 18 in which the cylinder is placed.

All portions of the electrical conductors are thoroughly insulated and held from contact with the casing, so that the latter may be grasped in the hand without danger of shock, and there can be no danger of grounding a portion of the current through the body in case the hand is immersed in the water while the heater is in operation.

The casing 18 is annular in cross section, comprising an outer tube 18 and an inner tube 19. This casing is hermetically sealed at both ends, and if necessary the air may be exhausted therefrom. The outer end of the casing is preferably rounded, although its shape at this point is not of material importance. From the end of the casing project a number of lugs 20 which serve to support the lower end of the casing slightly

above the bottom of the vessel in case the heater is placed in a vertical position. This will permit of the circulation of the water through the inner tube 19, no matter what 5 the position of the heater may be.

Secured to one end of the casing is a pair of tubes 21, containing wires 22 which are connected to the ends of the high resistance wire, and said wires extend through the tubes 10 to the handle. The handle is made in two sections, 23 and 24, the section 23 being provided with contacts 25 and 26 to which the ends of the wire 22 are connected. This portion of the handle has an end socket in 15 which the outer portion of the handle may be screwed, and the outer portion of the handle is provided with contacts 27 and 28, that are arranged to engage with the contacts 25 and 26, respectively.

20 The outer section of the handle is connected to current conducting wires 29 and 30, which may be connected at the opposite end to a suitable plug for insertion in a lamp socket or the like, and in this outer portion 25 of the handle is a rotary push button switch 31 that is connected between the wire 29 and the contact 27, while the wire 30 is extended directly to the contact 28. The rotary push button switch is of that type in which alternate 30 depressions will make and break the circuit, one depression closing the circuit in order to place the heater in operation, and the current continuing to flow through the high resistance wire until the button is again 35 depressed, this time for the purpose of breaking the circuit.

The outer section of the handle may be removed at pleasure, and when so removed there are no live wire connections which 40 might prove dangerous in the event of careless handling, the apparatus being constructed with a view of preventing accidental shocks, while in the hands of careless or inexperienced persons.

45 The device may be conveniently employed for the heating of small quantities of water in basins or similar vessels, or may be used for heating purposes generally if desired.

I claim:—

50 1. In an electric heater, a hollow cylindrical cylinder having on its periphery a double rib extending helically from end to end of the cylinder, one of the ribs being provided with an under-cut recess at a point near one end 55 of the cylinder to receive the bight of the wire and prevent its accidental displacement, and both of the ribs having openings near the opposite end of the cylinder, and a double resistance wire, the bight of which extends 60 through the under-cut recess, the wire being wound in the grooves between the ribs and the terminals of the wire passing through said openings.

2. In an electric heater, a cylinder of insulating material having wire receiving

grooves in its periphery, a resistance wire disposed between the grooves and having both of its terminals at one end of the cylinder, an annular metallic casing within which the cylinder is inclosed, a handle carrying 70 said casing, and current conducting wires extending through the handle and connected to the terminals of the resistance wire.

3. In an electric heater, a grooved cylinder of insulating material, a resistance wire 75 wound within the grooves and having its two terminals at the same end of the cylinder, a metallic casing inclosing the cylinder and including a pair of spaced tubes, the inner of which is open at both ends to permit the passage of liquid, a bifurcated handle secured to the cylinder, and current conductors extending through the handle and connected to the terminals of the resistance wire.

4. In an electric heater, a cylindrical support formed of insulating material and provided with peripheral grooves, a resistance wire wound within the grooves and having both of its terminals at the same end of the cylinder, an annular casing inclosing said support, the grooves being of sufficient depth to prevent contact between the wires and the outer portion of the casing, a handle member, a pair of tubes connecting the handle member to the casing, current conductors extending through the handle member and the tubes and connected to the terminals of the resistance wire, and a switch located in the handle.

5. In an electric heater, an annular casing arranged to form a central liquid passage, projections arranged at one end of the casing to permit free circulation of the liquid when the casing is placed on end, a handle secured to the opposite end of the casing, and a high 105 resistance conductor arranged within the casing and insulated therefrom.

6. In an electric heater, an annular casing having a central liquid passage, a handle secured to one end of the casing, a high resistance conductor arranged within and held from contact with all portions of the casing, current conductors extending through the handle and connected to the high resistance conductor, and lugs or projections disposed 115 at that end of the casing opposite the handle to permit the free circulation of liquid when the heater is placed on end.

7. In an electric heater, the combination with a casing, of a high resistance conductor arranged within and held from electrical contact with the casing, a two part handle comprising inner and outer detachable sections, contact members carried by the sections and arranged to engage with each other to complete a circuit, a controlling switch carried by the outer section of the handle, the outer section together with the switch and current conductors being detachable from the inner section.

8. In an electric heater, a casing, a high resistance conductor arranged within and insulated from said casing, a sectional handle for said casing, said sections having plug and socket connection, and the inner section having current conductors that are connected to the high resistance conductors, a switch carried by the outer section of the handle, and current conductors leading through such outer section, the switch being connected to one of said current conductors the outer sec-

tion of the handle, together with the switch and the outer current conductors being detachable from the inner section of the handle.

In testimony that I claim the foregoing as 15 my own, I have hereto affixed my signature in the presence of two witnesses.

JAMES A. REARDON.
